UNITED STATES PATENT OFFICE

LLOYD G. BLEYER, OF MILWAUKEE, WISCONSIN, ASSIGNOR TO CHAIN BELT COMPANY, OF MILWAUKEE, WISCONSIN, A CORPORATION OF WISCONSIN

ENDLESS TRAVELING WATER SCREEN

Application filed April 23, 1930. Serial No. 446,597.

This invention relates to endless traveling water screens and has for one of its objects to provide an automatic take-up device for screens of this character which will constantly take out the slack in the screen chains and maintain the same taut.

In order that the precise nature of the invention may be better understood it is said that in water screens of the endless type in which there is provided spaced head and foot sprockets about which are trained the endless chains which carry the screen baskets there is a constant tendency towards slackness in the said chains. This is due not only to the stretching and wear which commonly occurs in all chains, but also to the fact that because of the relatively great pitch of the chains, in some instances as much as two feet, and the consequent employment of sprockets having a relatively few number of teeth, there is a constant lateral movement of the back or down runs of the chain which, if not compensated for, tends to produce alternate slack and taut conditions.

In water screens of this type it is common to provide in the boot at the foot of the screen, trash seals which are formed through the co-operation of the side plates of the moving screen baskets with curved stationary plates in the boot, and since the clearances between these running seals is of necessity small, in order to prevent trash from finding its way through such seals, it is essential that the chains be maintained taut at all times in order to prevent contact and undue wear of these seal parts.

Due to the provision of these trash seals in the boot and also due to the fact that the boot is commonly located considerably below the water level and between masonry side walls where it is relatively inaccessible, it is not practical to make the foot sprocket adjustable for the purpose of taking up slack in the chains as has been heretofore proposed in connection with certain types of endless vertical conveyers. These conditions which exist in water screen practice, therefore make it practically essential that any take-up mechanism operate upon the head sprocket of the screen or at least that it be located above the

water level and away from the foot sprocket in order that the trash seals in the boot may be maintained.

It is the primary object of the present invention therefore, to provide an automatic take-up device for traveling water screens which operates to constantly and yieldably tend to move the head sprocket away from the foot sprocket in order that the chains may, at all times, be properly tensioned and that the trash seals in the boot be properly maintained in operative condition.

With the above and other objects in view which will appear as the description proceeds, the invention consists in the novel details of construction and combinations of parts more fully hereinafter disclosed and particularly pointed out in the appended claims.

Referring to the accompanying drawings forming a part of this specification in which like reference characters designate like parts in all the views:

Figure 1 is a side elevational view partly broken away of a well known form of endless traveling water screen with the present invention applied thereto;

Figure 2 is an enlarged front elevational view of the upper portion of the screen frame shown in Figure 1, showing the parts constituting the present invention applied thereto;

Figure 3 is a top plan view of the parts shown in Figure 2;

Figure 4 is a sectional elevational view taken approximately on the plane indicated by the line 4-4 of Figure 2, looking in the direction of the arrows;

Figure 5 is a fragmentary front elevational view, similar to Figure 2, of a slightly modified form of the invention;

Figure 6 is a sectional plan view of the parts shown in Figure 5 taken approximately on the plane indicated by the line 6-6 of the said figure; and

Figure 7 is a vertical sectional view taken approximately on the plane indicated by the line 7-7 of Figure 5.

Referring more particularly to Figures 1 to 4, inclusive, 10 indicates the main vertical frame members of the water screen which usually take the form of Z-bars, and which

are usually received in suitable guides set into the masonry walls 11 of the water conduit or flume. At the bottom of said members there is provided a boot 12 in which the 5 foot sprockets 13 are journalled and the said boot is provided with the stationary trash seal elements 14 and 15 which coact with the side plates 16 of the screen baskets in the well known manner, to prevent the passage 10 of trash around the screen at the points where the baskets pass through the boot. As will be readily understood by those skilled in the art the said screen baskets are carried by screen chains 17 which are trained around 15 the foot sprockets 13 as well as about the head sprockets 18, which latter are journalled in suitable bearings 19 as will be clear from Figure 1. The said bearings 19 are slidably mounted between the upright frame members 20, which constitute extensions of the main frame members 10, and guides 21, whereby the said head sprockets are free to slide vertically in order to maintain the 25 chains in taut condition.

25 As was above mentioned the pitch of chains 17 in apparatus of this character is relatively great and it is common to employ sprockets of relatively few teeth, usually five or six in number, five being shown in the present 30 drawings. It will be obvious from an inspection of Figure 1 that with the parts in the positions shown, as the head sprocket 18 moves in a counterclockwise direction from the position illustrated, through an arc of 35 approximately 36° the articulating center 22 of the chain will not only move downwardly but will move outwardly toward the left to approximately a point 23. The same outward movement of the back run of the screen will 40 take place at the foot sprocket 13 so that the entire back run will have been moved laterally toward the left from the positions shown in Figure 1.

45 There is also the same tendency of movement in the front or up-run of the screen, but this is prevented by the guide or seal members 24 which are ordinarily provided in screens of this type to prevent the passage of trash around the ends of the screen 50 baskets. It therefore results that since lateral movement of the front run is prevented while lateral movement of the back run is not prevented, the distance between the two runs is alternately greater and less as the screen is 55 moving, which in effect, is the same as shortening and lengthening the chain, and unless provision is made to take care of this movement it is necessary that the chains be initially placed on the sprockets in a slack condition 60 so that the said lateral movement may be accommodated. However, when the chains are thus slackened the trash seals in the boot 12 between the end plates 16 of the screen 65 baskets and the seal members 14 and 15 are permitted to contact with consequent heavy

wear upon the parts which necessitate frequent replacement of these seal elements.

In order to overcome these difficulties the bearings 19 are provided with upright rods or shafts 25, the upper ends of which are 70 threaded as at 26 and carry nuts 27 by means of which the head sprocket 18 may be properly positioned initially as will presently appear. Transverse levers 28 and 29 are pivoted respectively at 30 and 31 in ears or 75 brackets 32 carried by upright members 33 which are mounted upon the transverse frame member or beam 34. The outer ends 35 and 36 of the levers 28 and 29 are bifurcated and straddle the upright rods or shafts 25 as 80 clearly shown in Figures 2 and 3, beneath the nuts 27. The inner ends of the levers 28 and 29 overlap as clearly shown in the said figures and the said inner ends have hung upon them as between straps 37, a suitable weight 38. 85 The said weight 38 is always tending to lower the inner overlapping ends of the levers 28 and 29 and to therefore raise the outer bifurcated ends 35 and 36 of these said levers, which force is transmitted through the nuts 90 27 to the rods 25 and the slideable bearings 19 with the result that the head sprockets 18 are constantly urged upwardly thereby automatically taking up any slack in the screen chains 17. The force applied however is yieldable 95 so that when the back run of the chains moves outwardly from the positions shown in Figure 1, as above described, the head sprockets 18 may move downwardly to accommodate the apparent shortening of the chains. The 100 head sprockets constantly rise and fall during the operation of the screen and the chains 17 will at all times be maintained in a taut condition, whereby contact between the seal elements 14, 15 and 16 in the boot will be 105 prevented with a consequent elimination of wear upon these said elements.

A slightly modified form of the invention is illustrated in Figures 5, 6 and 7 in which a separate weight is applied to each side of the screen instead of a single weight as in the preceding form. In this said modified form the levers 28 and 29 are shortened somewhat and are connected through links 40, 41, and 42 to levers 43 which carry individual weights 44 which serve the same purpose as the weight 38 of the preceding form. In each form it will be understood that the head sprockets 18 are initially positioned through 110 adjustments of the nuts 27 upon the threaded ends 26 of the rods 25 after which the weights such as 38 and 44 will automatically take care of the tension upon the screen chains. In both forms of the invention shown slight 115 inequalities in the tension of the separate chains will be automatically taken care of as will be readily understood.

It is obvious that those skilled in the art may vary the details of construction as well as the precise arrangement of parts without 120

departing from the spirit of the invention, and it is not wished to be limited to the above disclosure except as may be required by the claims.

5   What is claimed is:

1. In an endless traveling water screen having a frame, a sprocket-carrying head shaft freely slidably mounted in said frame, a boot, a sprocket-carrying foot shaft in fixed relation to said boot, screw-threaded means for initially adjusting said head shaft relative to said foot shaft, and a long pitch screen-basket carrying chain trained about said sprockets, there being running trash seals 10 between fixed portions of said boot and portions of the screen baskets, the combination of levers fulcrumed to said frame, one arm of said levers engaging said screw-threaded means; and a weight operatively connected 15 to the other arms of said levers, for exerting a constant lifting force upon said head shaft to maintain said chains taut and prevent contact and wear between the trash seal parts in the boot.
2. In an endless traveling water screen, a frame; a boot; a sprocket-carrying head shaft slidably journaled on said frame for free movement toward and from said boot; long-pitch chains carrying screen baskets 20 trained about the sprockets on said head shaft and passing through said boot; running trash seals between said baskets and boot; a pair of levers pivoted to said frame and connected to the journals of said head shaft; and a single weight connected to both of said levers, whereby they constantly urge said shaft away from said boot and prevent contact and wear between the trash seal parts. 25

40   In testimony whereof I affix my signature.

LLOYD G. BLEYER.
